UNITED STATES PATENT OFFICE.

PHILLIPP F. FLAGGE, OF MILWAUKEE, WISCONSIN, ASSIGNOR TO MILWAUKEE CORRUGATING COMPANY, OF GREENFIELD, WISCONSIN, A CORPORATION OF WISCONSIN.

FOLD-OPENING MACHINE.

1,117,991.

Specification of Letters Patent.

Patented Nov. 24, 1914.

Application filed August 27, 1914. Serial No. 858,885.

To all whom it may concern:

Be it known that I, PHILLIPP F. FLAGGE, a citizen of the United States, residing at Milwaukee, in the county of Milwaukee and State of Wisconsin, have invented certain new and useful Improvements in Fold-Opening Machines, of which the following is a specification, reference being had to the accompanying drawing, forming a part 10 thereof.

The main object of this invention is to open or spread the closed transverse folds or joints at the ends of the sections of sheet metal eavestrough and the like, so that the 15 ends of adjoining sections can be readily entered therein and form tight joints therewith.

It consists in the construction, arrangement and combination of parts as hereinabove particularly described and pointed out 20 in the claims.

In the accompanying drawing like characters designate the same parts in the several figures.

Figure 1 is a plan view partly in section of a machine embodying the invention; Fig. 2 is a side elevation thereof; Fig. 3 is a longitudinal section on the line 3—3, Fig. 1; Figs. 4 and 5 are cross sections on the lines 30 4—4 and 5—5 respectively, Figs. 1 and 2 a part in Fig. 4 being broken away; Figs. 6 and 7 are partial sections like or similar to Fig. 3, showing the parts of the machine in different positions, and illustrating their 35 mode of operation; and Fig. 8 is an enlarged sectional view showing a fold as partially opened and left by the spreading blade of the machine.

The machine comprises a suitable bed or 40 frame 1, on which the various working parts are mounted. At one end the machine is provided with a holder comprising two parts adapted to clamp or confine between them an eaves-trough section or the like, having 45 a double fold at one end, one of these parts being movable toward and from the other. In the present case, one part of the holder consists of a head 2, having a convex semi-cylindrical face on the under side, fitting 50 the inside of a trough section. It is supported in a fixed position by a cross bar 3,

to which it is bolted or fastened on the upper side, the cross bar being supported adjacent to its ends by posts 4, which are fastened at their lower ends in or to the bed or frame. 55 The upper ends of the posts 4 are threaded, and the cross bar 3 is adjustably secured thereon by nuts 5, whereby the head 2 can be adjusted vertically for sheet metal of different gage or thickness. 60

The other part of the holder consists of a jaw 6, having a semi-cylindrical concave face approximately fitting the convex face of the head 2. The jaw 6 is movable vertically toward and from the head 2 on guides 65 7, fastened to and extending upwardly from the base or frame 1. Adjacent to its inner end the jaw 6 is formed on its upper side with a semi-annular recess 8, concentric with its concave face, to receive a double external 70 fold on the end of an eaves-trough section, as shown in Figs. 6 and 7. A shoulder 9, is formed by this recess for the outer fold to abut against at its front end. The head 2 is formed in its inner end and adjacent to 75 its upper side, with a transverse groove in which are movably fitted the squared shanks of inwardly yielding presser pieces 10, as shown in Figs. 1 and 4. The outer faces of these presser pieces, which normally project beyond the convex face of the head 2 on the opposite sides thereof and inwardly beyond its inner end, are rounded. The shanks of the presser pieces are offset forwardly at their inner ends, as shown in Fig. 80 1, and between them is inserted a spiral spring 11, their outward movement being limited by the engagement of the offset ends of the shanks with shoulders at the ends of the central portion of the groove, which is 85 deeper than the outer portions thereof. The shanks of the presser pieces 10 and the spring 11 are held in place by a cover plate 12, fastened to the end of the head 2.

A reciprocating head 13, guided between 90 longitudinal ways 14, on the base or frame 1, is movable toward and from the inner end of the holder, and is provided at the end adjacent thereto with a concave seat in which is secured by a bolt 15 and a clamping 100 block 16, a concave spreading blade 17.

The head 13 is connected by a pitman 18,

with a crank 19, which is journaled in bearings 20 on the base or frame 1, adjacent to the end opposite the holder. The pitman 18 has a lost motion connection with the head 13, which may consist as shown, of a pin 21, passing through the head of the pitman, in which it is secured by a bolt 22, into longitudinal slots 23, in upstanding parallel ribs or walls 24 on the head.

10 The jaw 6 is operated by a longitudinal slide bar 25, guided in a groove or channel in the under side of the head 13 on the bed or frame 1, and provided adjacent to its front end with a hardened steel block 26, formed with inclines on its upper side adapted to work with corresponding inclines on the under side of the jaw, as shown in Figs. 3, 6 and 7.

Adjacent to its rear end the slide bar 25 is formed or provided with two teeth or lugs 27, which project upwardly therefrom through a longitudinal slot 28 in the head 13, and between which the head 29 of the bolt 22 works, preferably with a certain 25 amount of play or lost motion.

The crank shaft is provided with a loose gear 30, or other rotary driver, loosely mounted thereon, and with a clutch 31, fixed on said shaft and having a spring actuated 30 pin or dog 32, adapted when released, to be thrust by its spring into engagement with the hub of the gear or driver.

A trip, which may consist of a bar 33 guided in a bracket 34 on the bed or frame 1, 35 and projecting normally at one end, which is formed with an incline, into a peripheral groove in the clutch 31, by engagement with a notch in the pin or dog 32 withdraws and holds said pin or dog out of engagement 40 with the gear 30, as shown in Fig. 1. At its opposite or front end the trip bar 33 is connected with one arm of a lever 35, fulcrumed on the base or frame 1, its other arm being connected by a rod 36 with a movable stop 45 or part 37, which is hinged or pivoted to the base or frame 1, and extends upwardly therefrom adjacent to the inner or rear end of the holder. The stop or part 37 is cut away on the upper side to clear the blade 13 and 50 permit its advance movement, as hereinafter explained. The trip bar 33 and the stop 37 are held in their normal positions as shown in Fig. 1, by a spring 38 connecting one arm of the lever 35 with the base or frame 1.

55 The forward movement of the stop 37 and the rearward movement of the trip bar 33 are limited by stop pins or projections 39, which project rearwardly from the jaw 6 and with which the stop 37 engages when it 60 is swung forward.

A brake wheel or drum 40, fixed on the crank shaft, and a brake band 41, fastened to the base or frame 1 and passing around said wheel or drum, prevent overthrow of 65 the crank shaft by its momentum when the

clutch pin 32 is withdrawn by the trip 33 from engagement with the gear or driver 30.

In the operation of the machine, the gear or driver 30 being constantly rotated, a trough section 42 or the like is inserted with 70 the end having the double fold 43 foremost between the head 2 and jaw 6 of the holder, and pushed against the pivoted stop 37, which is turned backward, as shown in Fig. 6, withdrawing the trip 33 and releasing the 75 clutch pin or dog 32. The clutch 31 being locked by the pin or dog 32 to the gear or driver 30, the crank 19 is turned one revolution. In the forward movement of the pitman 18 the bolt head or tooth 29 on its front 80 head is first carried into engagement with the front tooth or projection 27 on the slide bar 25, thrusting the block 26 with its inclines forward underneath the jaw 6, which is thus forced upwardly against the bottom 85 of the trough section or the like, thereby clamping or confining it against the head 2 of the holder, as shown in Fig. 6, with the fold 43 in the recess 8. The cross pin 21 is then brought into engagement with the front 90 ends of the slots 23, and pushes the head 13 with the blade 17 forward, the blade passing between the two outer leaves or layers of the fold and partially spreading or opening the fold, as shown in Figs. 7 and 8. The presser 95 pieces 10 thrust and hold the sides of the trough section or the like outwardly against the concave recessed portion of the jaw 6, and insure the blade 17 properly entering the fold 43. On the return movement of the 100 pitman 18, the bolt head or tooth 29 engaging with the rear tooth 27, withdraws the slide block 26, releasing the jaw 6, which is thus permitted to drop into its original position, as shown in Fig. 3, and release the 105 trough section. The cross pin 21 engaging with the rear ends of the slots 23, withdraws the head 13 and blade 17 rearwardly from the fold 43, leaving it in the shape and condition shown in Fig. 8. The forward thrust 110 of the blade 17 into the fold 43 is received and resisted by the shoulder 9 of the jaw 6, against which the forward end of the fold abuts. When the jaw 6 is released and falls, thereby releasing the trough section, the 115 pivoted stop or part 37 is tipped back forward to its original position, as shown in Fig. 3, by the spring 38 and the trip 33 is thrust backward into the path of the clutch pin or dog 32, which at the completion of 120 the revolution of the crank 19 is withdrawn from engagement with the gear or driver 30, thereby stopping the crank in the position in which it is shown in Figs. 1, 2 and 3. The trough section being withdrawn from the 125 holder and another inserted in its place, the operations of the several parts of the machine are repeated as above explained. As shown in Fig. 8, only a portion of the fold 43 is spread or opened, leaving the leaves or 130

layers adjacent to its inner or closed end close together, so as to pinch and form a tight slip joint with the end of an adjoining section when it is inserted in the fold. A tight joint is thus made without soldering, and at the same time, longitudinal expansion and contraction of the trough sections are provided for.

In the formation of the trough sections or the like, the folds 43 are pressed and left tightly together, so that in order to enter the plain end of one section between the outer layers of the fold 43 of another section in assembling the sections, it is necessary to partially spread or open the outer layers of the folds.

Various changes in details of construction and arrangement of parts may be made without departing from the principle and scope 20 of the invention as defined in the following claims.

I claim:

1. In a fold opening machine, the combination of a holder provided with means for 25 clamping a section of eaves-trough or the like in place therein, a reciprocating blade movable lengthwise of a trough section clamped in the holder and adapted on its advance to enter and open a transverse fold 30 thereof, and means for actuating said blade.

2. In a fold opening machine the combination of a holder provided with means for 35 clamping a section of eaves-trough or the like in place therein, a reciprocating head movable toward and from the holder and lengthwise of a trough section clamped therein, and provided with a spreading blade adapted to enter and open a transverse end fold of the trough section on the 40 advance movement of the head, and means for actuating said head and clamping means in proper order.

3. In a fold opening machine the combination of a holder comprising a stationary 45 head and a clamping jaw movable toward and from said head, a reciprocating head movable toward and from said holder and provided with a spreading blade adapted on its advance movement to enter and open a 50 transverse end fold of an eaves-trough section or the like clamped in said holder, a slide having an incline for operating the clamping jaw and a crank connected with and adapted to actuate the reciprocating 55 head and the slide.

4. In a fold opening machine the combination of a holder comprising a fixed head and a clamping jaw movable toward and from said head, a reciprocating head 60 movable toward and from said holder and provided with a spreading blade adapted on its advance movement to enter and open a transverse end fold of an eaves-trough section or the like clamped in said holder, a reciprocating slide for operating the clamp- 65

ing jaw, and a crank connected with said reciprocating head and slide and adapted to operate the slide in advance of the head.

5. In a fold opening machine the combination of a holder having means for clamping a section of eaves-trough or the like in place therein, a reciprocating head movable toward and from said holder and provided with a spreading blade adapted on its advance movement to enter and open a transverse fold of an eaves-trough section or the like clamped in said holder, a crank connected with said head, and a movable part adapted by engagement therewith of a trough section or the like as it is inserted in the holder, to start the crank.

6. In a fold opening machine the combination of a holder, a reciprocating spreading blade movable toward and from the holder and adapted on its advance to enter and open a transverse fold of an eaves-trough section or the like in the holder, a crank connected with said blade, a rotary driver, a clutch for operatively connecting the crank with the driver, a trip normally holding the clutch out of engagement, and a movable part connected with and adapted to withdraw the trip when a trough section or the like is inserted in the holder.

7. In a fold opening machine the combination of a holder having a fixed head and a jaw movable toward and from the head, a slide for operating said jaw, a reciprocating spreading blade movable toward and from the holder and adapted on its advance to enter and open a transverse fold on an eaves-trough section or the like in the holder, and a crank connected with said slide and having a lost motion connection with said blade.

8. In a fold opening machine the combination of a holder comprising a fixed convex semi-cylindrical head and a concave jaw approximately fitting and movable toward and from said head and having a recess forming a transverse shoulder in its concave face, inwardly yielding presser pieces connected with said head and projecting outwardly from opposite sides of its convex face adjacent to one end thereof, a reciprocating concave blade adapted on its advance to enter and open an external transverse fold on an eaves-trough section or the like confined between the head and jaw with its fold in the recess of the jaw, and means for operating said jaw and blade.

9. In a fold opening machine the combination of a holder having semi-cylindrical concave and convex interfitting parts one of which is movable toward and from the other, the concave part being recessed adjacent to one end to receive an external double fold at one end of an eaves-trough section or the like held between said parts and to form a shoulder for the fold to abut against,

a reciprocative concave spreading blade movable toward and from said holder and adapted on its advance to enter and open said fold for a portion of its width only
5 next to the end of the trough section or the like, the adjoining layers of the fold for the remainder of its width being closed, and means for actuating said blade.

In witness whereof I hereto affix my signature in presence of two witnesses.

PHILLIPP F. FLAGGE.
